UNITED STATES PATENT OFFICE.

CHARLES VAN CAPPELLEN, OF BRANDON, MINNESOTA.

DESIGN FOR A GAME-BOARD.

SPECIFICATION forming part of Design No. 28,438, dated March 29, 1898.

Application filed February 28, 1898. Serial No. 672,099. Term of patent 14 years.

To all whom it may concern:

Be it known that I, CHARLES VAN CAPPELLEN, a citizen of the United States, residing at Brandon, in the county of Douglas and State of Minnesota, have invented a new and original Design for a Game-Board, of which the following is a specification.

This invention relates to a new and original design for a game-board; and it has for its object to provide a design of this character that shall be both useful and ornamental.

The leading feature of the design resides in a game-board provided on its playing-surface with a field having a series of approximately concentric circular figures bounded by a continuous spiral line and a continuous series of approximately rectangular figures bounded by straight radial lines between the concentric circular figures.

A minor feature of the design resides in the playing-field of the game-board, having an elongated or oblong space lying within one of the circular figures and extending across a number of the rectangular figures therein.

In the drawings, Figure 1 is a plan view of a game-board embodying the herein-described design. Fig. 2 is a cross-sectional view of the game-board.

Referring to the accompanying drawings,

the numeral 1 designates a game-board provided with a flat surface 2, having thereon a field provided with a continuous spiral line 3. The spiral line 3 is arranged so as to produce a series of approximately concentric circular figures, and within the separate concentric circular figures is arranged a continuous series of approximately rectangular figures 4, which figures are bounded by straight radial lines 5, extending across the concentric spaces between the contiguous portions of this spiral line.

To complete the design, the plain field 2 of the game-board has arranged thereon an elongated or oblong space 6, lying within one of the concentric circular figures and extending across a number of the rectangular figures 4 therein.

What I claim is—

The design for a game-board herein shown and described.

In testimony that I claim the foregoing as my own I have hereto affixed my signature in the presence of two witnesses.

CHARLES VAN CAPPELLEN.
